Primary Examiner — Jeffrey D Asch
Assistant Examiner — Tracey J Bell

(57) **CLAIM**

I claim the ornamental design for a wrist band, as shown and described.

DESCRIPTION

FIG. 1 is a front view of the wrist band.

FIG. 2 is a rear view of the claimed design.

FIG. 3 is a left side view of the claimed design.

FIG. 4 is a right side view of the claimed design.

FIG. 5 is a top view of the claimed design.

FIG. 6 is a bottom view of the claimed design; and,

FIG. 7 is a perspective view of the claimed design.

The broken lines appearing on FIGS. 1, 2, 3, 4, and 7 of numerals and wording "Hydro-Band" are environmental matter forming no part of the claimed design.

1 Claim, 4 Drawing Sheets
